UNITED STATES PATENT OFFICE.

PATRICK J. COLLINS, OF SCRANTON, PENNSYLVANIA, ASSIGNOR, BY MESNE ASSIGNMENTS, TO GENERAL ELECTRIC COMPANY, A CORPORATION OF NEW YORK.

ELECTRIC-RAILWAY MOTOR.

No. 826,478.

Specification of Letters Patent.

Patented July 17, 1906.

Original application filed January 3, 1905, Serial No. 239,345. Divided and this application filed August 11, 1905. Serial No. 273,835.

To all whom it may concern:

Be it known that I, PATRICK J. COLLINS, a citizen of the United States, residing at Scranton, in the county of Lackawanna and State of Pennsylvania, have invented certain new and useful Improvements in Electric-Railway Motors, of which the following is a specification.

This invention relates to improvements in electric-railway motors of the kind shown in my copending application, Serial No. 239,345, filed January 3, 1905, of which this application is a division.

In the original application referred to I have shown several forms of railway-motors in which a plurality of armatures are arranged upon the car-axes and the truck-frame forms part of the magnetic circuit, the side bars of the truck-frames being connected by transverse partitions arranged between the armatures on adjacent axles and which form parts of the magnetic circuits.

In the present application transverse bars are arranged between the armatures on adjacent axles and longitudinally-extending bars or partitions are arranged between the armatures on each axle, these bars or partitions forming parts of the magnetic circuits.

In the accompanying drawings, Figure 1 is a plan view of a four-wheeled truck having two armatures on each axle, the truck-frame being divided longitudinally and transversely by partitions which form parts of the magnetic circuits. Fig. 2 is a plan view of a motor-truck similar to that shown in Fig. 1, the axles, however, having bars in the longitudinal partitions and each armature being arranged to operate but one car-wheel; and Fig. 3 is a section on the line 3 3 of Fig. 2, showing the tubular shafts or sleeves to which the armatures of the wheel are connected, said sleeves being mounted on the main axle, the armatures being shown in elevation and partly broken away.

Referring to the drawings, E indicates a rectangular steel or iron frame having the side bars e arranged outside of the car-wheel and resting upon the journal-boxes 1. These side bars are connected midway between the axles by a transverse steel or iron partition e', forming part of the magnetic circuit for the four motors shown, and the end bars e² are connected to the central partition e' by par-

titions e³, running longitudinally of the frame between the side bars.

The combined truck and field-magnet frame is thus divided into four compartments C³ C⁴ C⁵ C⁶. The axle 2 has two armatures D³ D⁴, secured to it and arranged within the compartments C³ and C⁵, respectively, and the axle 3 has two armatures D⁵ and D⁶, secured to it and arranged within the compartments C⁴ and C⁶, respectively. Pole-pieces 8² are arranged upon the end bars e² opposite the adjacent armatures, and pole-pieces 9^c, having windings 10^c thereon, are secured to the transverse partitions e' and project toward the armatures in the adjacent compartments of the frame. The partitions e' form parts of the magnetic circuits for the two motors in the compartments at each side of said partitions. The partitions e' in Fig. 1 may be provided with central bearings for the axles, if desired.

In Fig. 2 the construction and arrangement of the combined truck and field frame are the same as in Fig. 1. As shown in Figs. 2 and 3, however, bearings 5^b are arranged in the longitudinal partitions e³, and the armatures D³ and D⁴ upon each axle are mounted upon sleeves 15, so that they may rotate upon the axles 2 and 3. A car-wheel 4 is secured to each sleeve and rotates with the adjacent armature. It will be seen, therefore, that all of the car-wheels are driven independently by the armatures. The object of this construction is to permit the car-truck to turn on sharp curves without slippage of the wheels.

Any desired number of axles and partitions with pole-pieces between the axles may be added to the truck, and for such purposes as transfer-tables, where extended axles are provided with more than two wheels to run on several tracks, more than two armatures may be placed on each axle, the pole-pieces on the transverse bars of the frame being correspondingly increased and the longitudinal partitions being also increased, if desired.

What I claim as new, and desire to secure by Letters Patent, is—

1. In a motor-truck, the combination with parallel axles, and two armatures, and wheels mounted on each axle, of a combined field and truck frame comprising side bars supported upon the axles, said frame having

- also transverse bars, connected to the side bars, arranged at opposite sides of each axle, pole-pieces upon said transverse bars opposite the several armatures, and a partition 5 extending longitudinally of the truck between the armatures on the several axles and connected to said transverse bars, said bars and partition forming parts of the magnetic circuits.
10. 2. In a motor-truck, the combination with parallel axles, and two armatures and wheels mounted on each axle, of a combined field and truck frame comprising side bars supported upon the axles, said frame having also 15 transverse bars, connected to the side bars, arranged at opposite sides of each axle, pole-pieces upon said transverse bars opposite the several armatures, and a partition extending longitudinally of the truck between the armatures on the several axles and connected to said transverse bars, said partition having bearings resting upon the axles, and said bars and partition forming parts of the magnetic circuits.
20. 3. In a motor-truck, the combination with parallel axles, two armatures journaled upon each axle, and a wheel rotatable with each armature, of a combined truck and field frame having side bars supported on bearings resting upon said axles, said frame having also transverse bars, connected to the side bars and arranged at opposite sides of each axle, pole-pieces upon said transverse 25 bars opposite the several armatures, and a partition extending longitudinally of the frame between the armatures on the several axles and connected to said transverse bars, said partition having bearings resting upon the axles.
40. 4. In a motor-truck, the combination with parallel axles, two armatures journaled upon each axle, and a wheel rotatable with each armature, of a combined truck and field frame having side bars supported on bearings resting upon said axles, said frame having also transverse bars, connected to the side bars and arranged at opposite sides of each axle, pole-pieces upon said transverse 45 bars opposite the several armatures, and a partition extending longitudinally of the frame between the armatures on the several axles and connected to said transverse bars, said partition having bearings resting upon the axles.
45. 5. In a motor-truck, the combination with parallel axles, two armatures journaled upon each axle, and a wheel rotatable with each armature, of a combined truck and field frame having side bars supported on bearings resting upon said axles, said frame having also transverse bars, connected to the side bars and arranged at opposite sides of each axle, pole-pieces upon said transverse 50 bars opposite the several armatures, and a partition extending longitudinally of the frame between the armatures on the several axles and connected to said transverse bars, said partition having bearings resting upon the axles.
55. 6. In a motor-truck, the combination with parallel axles, two armatures journaled upon each axle, and a wheel rotatable with each armature, of a combined truck and field frame having side bars supported on bearings resting upon said axles, said frame having also transverse bars, connected to the side bars and arranged at opposite sides of each axle, pole-pieces upon said transverse 60 bars opposite the several armatures, and a partition extending longitudinally of the frame between the armatures on the several axles and connected to said transverse bars, said partition having bearings resting upon the axles, and said bars and partition forming parts of the magnetic circuit.
- In testimony whereof I affix my signature in presence of two witnesses.
